UNITED STATES PATENT OFFICE.

ALBERT ACKRON, OF PITTSBURGH, PENNSYLVANIA.

GAS-SAVING ATTACHMENT FOR BURNERS.

1,395,979.

Specification of Letters Patent.

Patented Nov. 1, 1921.

Application filed March 3, 1921. Serial No. 449,302.

To all whom it may concern:

Be it known that I, ALBERT ACKRON, a citizen of the United States, and residing in the city of Pittsburgh, in the county of 5 Allegheny and State of Pennsylvania, have invented or discovered new, useful, and Improved Gas-Saving Attachments for Burners, of which the following is a specification.

My invention consists in a new and im- 10 proved gas-saving attachments for burners.

While my invention may be used advantageously in connection with appliances for burning any character of gaseous fuel, natural or artificial, the especial purpose for 15 which my invention was devised is to meet the failing supply and the consequently irregular and low service pressure of natural gas which is extensively used for domestic purposes in many parts of the country.

20 Experiments conducted by Government agencies show that by moving the gas flame nearer the utensil, water coil or other object to be heated, satisfactory results can be obtained with a very short flame and a 25 very low service pressure.

In the case of many of the gas burning appliances now installed, the raising of the burners is difficult and expensive, and in some cases impossible.

30 The object which I have in view is the provision of inexpensive yet efficient means whereby the raising of the burners in such appliances will be rendered unnecessary while all of the beneficial results of such 35 alteration may be obtained at slight expense.

My improved burner attachment not only elevates the flame so that a shorter flame and a lower service pressure may be success- 40 fully used, but I also obtain complete combustion of the fuel and an improved and uniform application of the heat.

In the accompanying drawing, Figure 1 is a top plan view of a gas saving attach- 45 ment embodying the principles of my invention; Fig. 2 is an elevation of the same shown mounted on a ring burner, the attachment being broken away in section to show construction and the burner being indicated in dotted lines; Fig. 3 is a similar view showing a modified form of the attachment mounted on a gas burner having no axial well or opening, and also showing the attachment provided with a top plate of fire-

proof material; and Fig. 4 is a similar view 55 of another modification.

The following is a detailed description of the drawings, reference being first had to Figs. 1 and 2.

A represents my improved gas-saving at- 60 tachment which is preferably made of metal and may be either pressed or cast in shape; preferably cast. The attachment is mounted as shown on the ordinary gas burner of a heating appliance, such as a range or water 65 heater. Thus I have indicated in dotted lines at B a gas burner of the ring type having an axial well or depression.

The attachment is provided with a perime- 70 tral, downwardly and outwardly inclined apron 1 whose outer edge may rest on the burner to support the cap in place. The attachment is also provided with a down- 75 wardly extending axial throat 2 which is in- tended to be inserted down into the central well of the burner B to prevent the attachment from being accidentally knocked out of position. 3 is an annular horizontal portion surrounding the upper end of the throat 2, and 4 is an annular raised portion inter- 80 posed between portions 1 and 3. The raised portion 4 is provided with arcuate slots 5 for the upward flow of the gas flames.

At 6 I show in dotted lines ports in the upper wall of the throat 2 which may be 85 provided for the admission of air to be mixed with the burning gas ascending from the burner B.

When the gas is turned on in the burner 90 B, it rises from the usual burner perfora- 95 tions and ascends through the arcuate slots 5, forming the very desirable ring flame under the utensil. If the ports 6 are provided and there is available a good pressure of gas, the gas flames may pass through said ports 6 into the throat 2 and burn at the center of the attachment, thus heating di- rectly the central bottom of the utensil.

In Fig. 3 I show the throat 2 shortened to permit the attachment being mounted on 100 a star shaped burner C or a burner unpro- vided with a central well or marked de- pression.

I also show in Fig. 3 the use of a plate or disk D, of asbestos composition, stove 105 clay or other fire-proof material, which fits in the space 3 and closes the upper end of the throat 2. I prefer to provide the disk

D with a differential edge so as to engage the raised portion 4 without, however, blocking the slots 5. The disk D becomes highly heated and greatly aids in applying a uniform heat to the utensil to which the heat is being applied.

In Fig. 4 I show the throat 2 provided with a circumferential shoulder 7 which limits the downward insertion of the throat 10 2 in the central well of the burner B, thus holding the apron 1 above the burner B and thereby admitting air beneath said apron.

The results obtained by the use of my improved burner attachment have been most 15 satisfactory. The flame is brought close up under the utensil or water coil so that the full heating effect of a short flame is obtained, and good results are assured even when the service pressure is very low or 20 irregular.

All the gas issuing from the burner is utilized in combustion.

The fact that the slots 5 are formed in the highest portion of the attachment acts 25 to facilitate the passage of the gas flames to the point of ignition and prevents their being pocketed or husbanded within the cap instead of being conveyed to the flame openings. This is proved by the fact that there 30 is no lateral escape of unburned gas so characteristic of improperly designed devices for the purposes in question.

The attachment is inexpensive and easy to apply, and is also durable.

35 What I desire to claim is:—

1. A fuel saving attachment for gas burners adapted to be superimposed on the burner and comprising a central downwardly extending cylindrical throat, an annular horizontal portion surrounding the upper end of said throat, an annular raised portion, surrounding said annular horizontal portion, and provided with gas openings, and a downwardly and outwardly inclined perimetral apron surrounding said raised portion.

50 2. A fuel saving attachment for gas burners adapted to be superimposed on the burner and comprising a central downwardly extending cylindrical portion adapted to be inserted into the central well of the gas burner, an annular horizontal portion surrounding the upper end of said cylindrical portion, an annular raised portion surrounding said annular horizontal portion, and provided with gas openings, and an outwardly and downwardly inclined perimetral apron surrounding said raised portion.

55 3. A fuel saving attachment for gas burners adapted to be superimposed on the burner and comprising a central downwardly extending cylindrical throat, an annular horizontal portion surrounding the upper end of said throat, an annular raised portion, surrounding said horizontal portion, and

provided with a plurality of arcuate slots concentric with said attachment, and a downwardly and outwardly inclined perimetral apron surrounding said raised portion.

4. A fuel saving attachment for gas burners adapted to be superimposed on the burner and comprising a central downwardly extending cylindrical portion adapted to be inserted into the central well of the gas burner, an annular horizontal portion surrounding the upper end of said cylindrical portion, an annular raised portion surrounding said annular horizontal portion and provided with a plurality of arcuate slots concentric with the attachment, and a downwardly and outwardly inclined perimetral apron surrounding said raised portion.

5. A fuel saving attachment for gas burners adapted to be superimposed on the burner and characterized by a central circular depression, an annular raised portion surrounding said depression, and provided with gas openings, and a downwardly and outwardly inclined apron surrounding said raised portion.

6. A fuel saving attachment for gas burners adapted to be superimposed on the burner and characterized by a central circular depression, an annular raised portion surrounding said depression and provided with gas openings, a downwardly and outwardly inclined apron surrounding said raised portion, and a cylindrical portion depending axially from said attachment.

7. A fuel saving attachment for gas burners adapted to be superimposed on the burner and characterized by a central circular depression, an annular raised portion surrounding said depression, and provided with gas openings, a downwardly and outwardly inclined apron surrounding said raised portion, and a cylindrical throat depending axially from said attachment and provided with lateral ports in its upper wall.

8. A fuel saving attachment for gas burners adapted to be superimposed on the burner and characterized by a central circular depression, an annular raised portion surrounding said depression and provided with gas openings, a downwardly and outwardly inclined apron surrounding said raised portion, and a disk of fire-proof material seated in said central depression.

9. A fuel saving attachment for gas burners adapted to be superimposed on the burner and characterized by a central circular depression, an annular raised portion surrounding said depression and provided with gas openings, a downwardly and outwardly inclined apron surrounding said raised portion, a disk of fire-proof material seated in said central depression, and a cylindrical portion depending axially from said attachment.

10. A fuel saving attachment for gas burn-

ers adapted to be superimposed on the burner and characterized by a central circular depression, an annular raised portion surrounding said depression and provided with 5 gas openings, a downwardly and outwardly inclined apron surrounding said raised portion, a disk of fire-proof material seated in

said central depression, a cylindrical throat depending axially from said attachment and provided with lateral ports in its upper wall. 10

Signed at Pittsburgh, Pa., this 28th day of Feby., 1921.

ALBERT ACKRON.
